UNITED STATES PATENT OFFICE.

LOUIS F. HAGEMAN, JR., OF NIAGARA FALLS, NEW YORK, ASSIGNOR TO AMERICAN SALES BOOK COMPANY, LIMITED, OF TORONTO, CANADA, A CORPORATION OF ONTARIO.

SALES-CHECK HOLDER.

1,157,217.

Specification of Letters Patent.

Patented Oct. 19, 1915.

Application filed January 20, 1912. Serial No. 672,441.

To all whom it may concern:

Be it known that I, LOUIS F. HAGEMAN, Jr., a citizen of the United States, residing at Niagara Falls, in the county of Niagara and State of New York, have invented certain new and useful Improvements in Sales-Check Holders, of which the following is a full, clear, and exact description, such as will enable others skilled in the art to which it appertains to make and use the same.

This invention relates to sales check holders and the like.

One of the objects of the present invention is to provide a simple and practical device of the above character which may be easily and quickly manipulated.

Another object is to provide a device of the above character which will be durable in construction and inexpensive to manufacture. Another object is to provide a compact and self-contained device of the above character.

A further object is to provide practical means for preventing fraud in the use of devices of the above character.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of this invention: Figure 1 is a side elevation of the complete device in operative position. Fig. 2 is a similar view of the holder, taken from the opposite side, in open position; Fig. 3 is a rear end view with the parts in open position; Fig. 4 is a top plan view of Fig. 1; and Figs. 5 and 6 are detail sectional views of the locking means in locked and unlocked positions respectively.

Similar reference characters refer to similar parts throughout the several views of the drawing.

Referring now to the drawing in detail, there is denoted at 1 a casing, preferably formed of a single piece of stamped sheet metal bent in U shape to inclose the bottom and two sides thereof. The casing is partially permanently open at one of the other sides, hereinafter referred to as the front

side 2, while the opposite or rear side is closed by a swinging door 3 hinged at 4 to the lower part of the casing. The top is adapted to be closed by a second swinging door 5, which has directly connected therewith a third door 6 adapted to partially close the front opening 2 when the device is in closed position as shown in Fig. 1. This door 6 not only prevents access to the stubs of the three pads, shown at 7, 8 and 9, as well as the locking means hereinafter described, but also acts as a gripper member and exerts a downward pressure on the pads to prevent relative movement thereof.

To the bottom of the casing is secured a plate 10 extending outwardly through the front opening 2 adapted to support the leaves of the pads. This plate also permits the pads to be readily inserted or the stubs removed over the hinge 4 and the edge of the door which is slightly above the upper surface of the bottom of the casing proper when the door is open. A hook 11 may be secured to the bottom of the casing in order that the device may be suspended from the belt of the operator.

As is well known, devices of this character are frequently used in connection with lunch rooms, where the flexible leaves of the pads, which are provided with columns of numbers, are removed and punched according to the amount ordered. Heretofore devices of this character have required a separate punch, carried by the operator or waiter, and in order to provide a practical and self-contained device free from objections incident to former devices the present invention has the punch directly connected therewith. This punch is shown more clearly in Fig. 3 and includes a rod or member 12 passing through the upper part of the casing, provided at one end with a push button 13 and at its opposite end with a male punch 14. This punch is adapted to pass through a hole 15 in a female member 16 secured to and spaced from the side of the casing in any desired manner.

It will thus be seen that a check, after being torn from the pad, may be interposed between the member 16 and the side of the casing and the punch actuated to mark or perforate the number corresponding to the amount ordered.

In order to prevent the loss or theft of the pads of checks in devices of this style it is

desirable to provide a convenient form of locking means for the pad holder or casing, the key to which is usually held by the cashier. The key, however, is not always obtainable or is lost so that there is more or less inconvenience at all times. A similar result, however, may be attained, and without these objections, by providing a seal to the pad holder, which is broken whenever the holder is opened to remove or exchange the pads. In the present device the rear door 3 is provided with a resilient catch 17 adapted to engage a slot 18 in a co-acting member 19, whereby the door, on being closed, snaps into locked position. The member 19 in which the slot 18 is formed is provided at its opposite end with a second slot 20 through which a screw 21 passes to hold the member 19 in place and yet permit a relative sliding movement thereof. A cam 22 positioned at one side of this member is adapted to engage a seal defacing member comprising a resilient spring arm 23, the free end 24 of which is adapted to create a visual signal as by perforating or marking a seal 25 of celluloid, parchment or other distinctive brittle material covering the under side of the opening 26.

In normal or closed position the member 19 is positioned at the left, Fig. 5, whereby the cam 22 holds the member 24 out of contact with the seal. On moving the member 19, which may be conveniently done by engaging a depressed lug 27 with a knife or coin (Fig. 4), and moving the same to the right in a slot 28 in the top plate 5, it will carry the cam 22, Fig. 5, out of engagement with the resilient arm 23 and permit the perforator to break the seal 25, Fig. 6.

A convenient method of operating a device of this character is substantially as follows: The pad holder is normally suspended from the belt of the waiter by the hook 11, and on presenting a check the holder is removed from the belt, the top leaf of the pad removed and placed in operative relation to the punch 14 as shown by dotted lines in Fig. 4 in order to perforate a number according to the amount ordered. When the pads are exhausted the waiter is obliged to go to the cashier or manager for new pads, whereupon the manager first inspects the seal through the opening 26 to see if the device has been tampered with, and if all right, moves the lug 27 to the right, which permits the seal to be broken by the perforator 24 and also releases the catch 17 from its engagement with the slot 18 as the block 19 moves out of engagement therewith. The rear door is then opened and the stubs of the pads removed. The new pads are inserted through the rear opening, plates 29 passing between the top and bottom leaves thereof, according to their location, until they engage the bindings of the pads. In this

manner it is impossible, without destroying the pad, to draw the same out through the front opening. The manager then moves the member 19 to its locking position, the perforator 24 having been restored to normal position by the engagement of the cam 22 therewith and inserts a fresh seal over the opening 26. All this is done while the doors are in substantially the position shown in Fig. 2. The door 5 is then swung downwardly causing the door 6 to press down upon the top of the pads, grip the same intermediate the ends thereof, and hold the same in position. The rear door 3 is closed and the catch 17 snaps into the slot 18, thus firmly locking the device and all three doors in closed position. The door 5 and member 19 may be beveled at 30 and 31 to facilitate matters if desired. The holder is then ready for further operation when necessary.

It is thus seen that this invention provides a simple and practical device accomplishing, among others, all of the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a device of the character described, in combination, a casing adapted to hold a set of leaves and having a permanently open side through which said set of leaves is adapted to extend, movable adjacent walls, a gripper member associated with one of said walls, said adjacent walls being movable into positions to form sides of said casing and to cause said gripper member to grip said set of leaves, a catch on one of said walls and a catch member on another of said walls adapted to coöperate with said first catch to secure said walls in casing-forming position and said gripper member in gripping position.

2. In a device of the character described, in combination, a casing adapted to hold a set of leaves and having a permanently open side through which said set of leaves is adapted to extend, movable adjacent walls, a gripper member associated with one of said walls, said adjacent walls being movable into positions to form sides of said casing and to cause said gripper member to grip said set of leaves, a catch on one of said walls, and a catch member on another of said walls adapted to coöperate with said first catch to secure said walls in casing-forming position and said gripper member

in gripping position, and means adapted to disengage said catch members.

3. In a device of the character described, in combination, a casing adapted to hold a set of leaves and having a permanently open side through which said set of leaves extends, movable adjacent walls, a gripper member associated with one of said walls, said adjacent walls being movable into positions to form sides of said casing and to cause said gripper member to grip said set of leaves, a catch on one of said walls, a catch member on another of said walls cooperating with said first catch to secure said walls in casing-forming position and said gripping members in gripping position, means for disengaging said catch members, and a seal defacing member operated by said disengaging means.

20 4. In a device of the character described, in combination, a casing permanently open at one side and adapted to receive a set of leaves, a wall opposite said open side, movable to permit the set of leaves to be moved relative to said casing, and means adapted to grip the set of leaves to hold a portion of each leaf in said casing.

5. In a device of the character described, in combination, a casing permanently open at one side and adapted to receive a plurality of pads, a wall opposite said open side, movable to permit the plurality of pads

to be introduced into said casing, gripping means adapted to prevent relative movement of said pads in said casing, and means 35 adapted to prevent the removal of the stubs of said pads except in the path of their introduction.

6. In a device of the character described, in combination, a casing having a permanently open side and a plurality of movable walls, one of said walls being movable to permit the introduction of a set of leaves into said casing, another of said walls having a gripper member associated therewith, 45 and means whereby said first and second movable walls are adapted to coact in locking engagement to grip said set of leaves and hold a portion of each leaf against withdrawal from the casing.

50 7. In a device of the character described, in combination, a casing adapted to hold a pad and having an open front side, a swing door adapted to close the top, a flange on said door adapted to partially close the front opening, a door adapted to close the rear of said casing and a locking means adapted to hold said doors in normal locked position.

In testimony whereof I affix my signature, in the presence of two witnesses.

LOUIS F. HAGEMAN, JR.
